CLAIM

The ornamental design for a fire escape kit for building emergencies, as shown and described.

DESCRIPTION

FIG. 1 is a perspective view of a fire escape kit for building emergencies showing my new design, with the panel removed for clarity of illustration only;

FIG. 2 is a front elevational view thereof;

FIG. 3 is a rear elevational view thereof;

FIG. 4 is a side elevational view thereof, the side opposite being a mirror image of the side shown in FIG. 4; and,

FIG. 5 is a top plan view thereof, the bottom view being a mirror image of the top view shown in FIG. 5.

FIG. 1

FIG. 2

FIG. 3

FIG. 5

FIG. 4
